UNITED STATES PATENT OFFICE.

AZEL C. HOUGH, OF JANEVILLE, WISCONSIN.

DESIGN FOR A PORCH-SHADE.

49,800.

Specification for Design.

Patented Oct. 24, 1916.

Application filed November 7, 1913. Serial No. 799,827. Term of patent 14 years.

To all whom it may concern:

Be it known that I, AZEL C. HOUGH, a citizen of the United States of America, residing at Janesville, in the county of Rock and State of Wisconsin, have invented a new, original, and ornamental Design for Porch-Shades, of which the following is a specification, reference being had to the accompanying drawing, forming part thereof.

The figure is a side elevation of a portion of a porch shade, showing my new design.

I claim:

The ornamental design for a porch shade, as shown.

AZEL C. HOUGH.

Witnesses:

A. C. FAIRBANKS,
F. A. CUTTER.
